CORDED EDGE ARTICLE

Elmer G. Overly, Oakmont, Pa.

Application January 29, 1938, Serial No. 187,754

7 Claims.

(Cl. 154—52)

This invention relates to articles of sheet material having corded edges, and more particularly to articles of transparent, waterproof, sheet material such as shower curtains, garment bags and waterproof garments.

In a form which has been found particularly desirable and advantageous, the invention is embodied in articles composed of transparent, inelastic, chlorinated, rubber of the kind sold commercially under the name of "Pliofilm".

The invention is applicable either to hems or to bond edges, and to articles made up of one or more sheets of body material.

In the case of the hemmed edge, the corded edge is characterized by having the body material folded around a cord and then having the extreme margin of the material folded under to extend outward toward or to the cord. The three plies of superposed material are then secured to one another by through stitching to provide a hem free from exposed raw edges, and to provide a corded edge which is free from creases or sharp bends.

In the case of the bound edge, a cord is disposed along the raw edge or edges of one or more sheets of the body material, and a binding strip is folded around the cord to overlie the opposite margins of the body sheet or sheets. The extreme longitudinal marginal portions of the binding strip are folded over to extend outward toward the cord and the four plies of the binding strip thus produced are secured to one another and to the interposed margin or margins of the body sheet or sheets by through stitching. The resulting binding is free from exposed raw edges, while the cord maintains the binding strip along the edge of the composite structure free from creases or sharp bends.

In connection with waterproof, transparent material, the cord presents an ornamental appearance through the surrounding material, and is protected from dirt and water by the surrounding material, so that the originally attractive and ornamental appearance of the structure is maintained throughout a long period of use.

In all cases the cord constitutes a reinforcement protecting the sheet material from tearing in the marginal area, the area, that is, which is most likely to be exposed to tearing strains.

Other objects and advantages of the invention will hereinafter appear.

In the drawing forming part of this specification and illustrating certain advantageous and practical embodiments of the invention:

Fig. 1 is a plan view of the open end of a garment bag having a corded, bound edge constructed in accordance with one form of the invention;

Fig. 2 is a view in front elevation, partly broken away, and on a smaller scale than Fig. 1, of the garment bag illustrated in Fig. 1;

Fig. 3 is a fragmentary edge view of a shower curtain having a bound, corded edge; and

Fig. 4 is an edge view of a shower curtain having a hemmed corded edge.

In the illustrative embodiment of Figs. 1 and 2, the bag 1 comprises front and back sheets 2 and 3 of body material. Any suitable sheet material may be utilized, but the invention is practiced most advantageously by making the sheets 2 and 3 of transparent, inelastic, chlorinated rubber of the kind sold commercially under the name "Pliofilm". A flexible cord 4 is disposed along the side and bottom edges of the sheets 2 and 3, and is secured in place by means of a binding strip 5. The binding strip is desirably of the same material as the body sheets 2 and 3. The binding strip 5 is wrapped inward around the cord to overlie the adjacent margins of the sheets 2 and 3, and the longitudinal marginal portion of the binding strip are folded under to extend outward toward the cord as illustrated in Fig. 1. There are thus provided four superposed plies of the binding strip 5, two of the plies 6 and 7 extending over the margins of the body sheet 3, and the other two plies 8 and 9 extending over the margins of the body sheet 2. Through stitching 10 is applied to secure the plies 6, 7, 8 and 9 and the interposed margins of sheets 2 and 3 to one another.

It will be observed that the resulting, bound, corded edge is free from exposed raw edges, and that the portion of the binding strip which surrounds the cord 4 is supported by the cord in a manner to preclude creases or sharp bends.

When a transparent binding strip is utilized, the cord 4 is visible through the binding strip and presents an ornamental and attractive appearance. When the binding strip is both transparent and waterproof, the cord 4 is exposed to view and preserves its original ornamental and attractive appearance, because it is effectively protected against exposure to dirt and water by the binding.

While the corded edge has been described in connection with Figs. 1 and 2 as extending around three of the four edges of the bag 1, it will be appreciated, of course, that the invention might be practiced by running a corded edge of the kind

described along a single edge of a sheet structure or along a part only of a single edge.

In Fig. 3 disclosure is made of a shower curtain 11 which is the same in all respects as the bag structure illustrated in Figs. 1 and 2, save only that a single sheet 2a of the body material is employed. The sheet 2a is provided with a corded bound edge like the corded bound edge of Fig. 1. A detailed description of the parts making up the corded bound edge is deemed unnecessary in view of the description which has been given of Fig. 1. No detailed description will therefore be given, but corresponding reference numerals have been applied to corresponding parts with the subscript *a* added.

In Fig. 4 disclosure is made of a corded, hemmed edge applied to a single ply article such as a shower curtain 12. A cord 4b is laid upon the margin of the sheet 12 and the margin is folded around the cord and over the body part of the sheet 12. The extreme longitudinal margin 13 of the sheet is folded in to extend outward along the body portion of the sheet 12 toward the cord, so that in the marginal portion the sheet provides successive plies 14, 13 and 15 in superposed relation. The three plies 14, 13 and 15 are secured together by a line of through stitching 10b.

In this form of construction, as in those already described, flexible, inelastic, transparent, waterproof material of the kind already referred to may be employed to best advantage.

The invention is also capable of use, however, in connection with sheet material of any kind which admits of folding and stitching. The hemmed, corded edge of the Fig. 4 construction has the same advantages which have already been pointed out in connection with the bound corded edges of Figs. 1, 2 and 3. The hemmed, corded edge may, of course, be applied to plural ply bodies.

I have described what I believe to be the best embodiments of my invention. I do not wish, however, to be confined to the embodiments shown, but what I desire to cover by Letters Patent is set forth in the appended claims.

I claim:

1. An article of sheet material having a corded edge, said article including, in combination, a body of sheet material, a cord disposed along an edge of the body, a binding strip folded around the cord and over the opposite faces of a margin

of the body and having its extreme marginal portions folded under and disposed to extend toward the cord, and a substantially continuous line of through stitching extending substantially parallel to the cord and uniting both doubled margins of the strip with one another and with the interposed marginal portion of the body.

2. An article of sheet material having a corded edge, as set forth in claim 1 in which the body material and the binding strip are formed of flexible, transparent material.

3. An article of sheet material having a corded edge, as set forth in claim 1, in which the body material and the binding strip are formed of sheets of flexible, transparent inelastic chlorinated rubber.

4. An article of sheet material having a corded edge as set forth in claim 1, in which the body edge to which the corded edge construction is applied is of plural ply construction.

5. An article of sheet material having a corded edge as set forth in claim 1, in which the body edge to which the corded edge construction is applied is of single ply construction.

6. An article having a corded edge comprising, in combination, a flexible cord, a sheet of flexible transparent, sheet material wrapped around the cord and having the parallel zones extending inwardly from opposite sides of the cord disposed in superposed relation, with a marginal portion of at least one of said zones folded under between them, to extend outward toward the cord, and a substantially continuous line of through stitching extending substantially parallel to the cord and uniting said superposed sections and the interposed marginal material.

7. An article having a corded edge comprising, in combination, a main body portion made of a sheet of flexible transparent sheet material, a flexible cord, and a marginal zone made of the same material and integral therewith, said marginal zone being wrapped over the cord and folded over the main body portion, and having a portion folded under and extended outwardly toward the cord and between the marginal zone and the main body portion, and a substantially continuous line of through stitching extending substantially parallel to the cord and uniting said main body portion to said zone and interposed marginal material.

ELMER G. OVERLY.
